TIPPING FRAME FOR WAGONS

Max Roedel, Munich, Germany, assignor to F. X. Meiller, Maschinenfabrik & Wagenbauanstalt, Munich, Germany

Application November 15, 1938, Serial No. 240,543
In Germany May 8, 1937

1 Claim. (Cl. 296—28)

For tipping the bodies (wagon boxes and the like) of wagons, frames are mostly used which consist of two longitudinal girders connected by transverse girders and often with corner struts. 5 These rectangular tipping frames are sufficiently rigid to impart the necessary strength to the bottom of the body during lateral and rearward tipping but the tipping frames, in spite of the very strong and heavy girders, are not capable of withstanding all stresses occurring during the tipping operation. Thus, for example when the load slides laterally, the rectangular tipping frame is always stressed unequally with the result that stresses occur in the frame which twist 10 it and result in deformation of the wagon body. The side plankings of the wagon box then gape and the latches and hooks can only be closed with difficulty. These objections are particularly apparent in wagons tilting in three directions. Another disadvantage is that the tip bearing points for the lateral tipping are very 15 far away from the longitudinal girders, so that long tip bearing arms are necessary which must be very strong to avoid bending. In the known tipping frames the engagement of the hydraulic jack is confined to a certain point not too far from the middle of the frame and cannot be changed, as is often necessary, according to the 20 different requirements which the wagon has to meet.

This invention relates to a tipping frame which overcomes all these difficulties and is further characterized in that it can be made much lighter and consequently requires considerably 25 less material for its production than the tipping frames hitherto used.

The invention is characterized chiefly in that the tipping frame consists of two oblique intersecting longitudinal girders, which extend past the tip bearing points in close proximity thereto. The oblique intersecting frame can have a transverse girder in the middle so that a star-shaped frame is formed.

Several embodiments of the invention are illustrated by way of example in the accompanying drawing, in which:

Fig. 1 is a side elevation of a tipping frame,
Fig. 2 is a top plan view of Fig. 1,

Figs. 3 to 5 each show on a smaller scale a tipping frame of modified construction in top plan view.

The tipping frame according to Figs. 1 and 2 consists of two oblique, intersecting, longitudinal girders *a*, *a* which are preferably of U-section, but might also be of T-, H-, tubular or

angular section. As shown in Fig. 1, they are preferably higher in the middle than at their ends but may be of uniform height throughout their entire length. At a sufficient distance from the middle the longitudinal girders are 5 bent off so that they form two sections *a'* extending parallel to the axis of the wagon. The bridge *b* of the wagon box *c* rests on the longitudinal girders; *d* is a discharging bar.

The longitudinal girders *a*, *a* lie at such an 10 angle that they come within close proximity to the tip bearing points in such a manner that only very short stub-like tip bearings *e* are necessary. At the point of intersection of the oblique intersecting girders a counter-bearing 15 is provided for the engagement of the jack *f*. The counter-bearing may, as is customary, consist of a cup *g* to which the longitudinal girders *a*, *a'* are connected in a suitable manner, for example by bolts or rivets, but preferably by 20 welding.

At the point of intersection of the longitudinal girders *a*, *a* a transverse girder *h* of T-, H-, 25 U-, tubular or angular section is provided for additionally stiffening the cross frame so that the tipping frame has the shape of a star.

If the hydraulic jack *f* is to engage not in the transverse axis but laterally thereof, the tipping frame is constructed as shown in Fig. 3 so that the longitudinal girders *a* form triangles 30 with sides of different lengths. The cup *g* can therefore be located on the right or left of the transverse axis. It may also be located laterally of the longitudinal axis.

Fig. 4 shows a form of construction, in which 35 the point of engagement for the hydraulic jack can be changed as desired. For this purpose the tipping frame has a head plate *i* which is connected to the girders and rests on a transverse bar *k* in such a manner that the jack *f* 40 can engage in the angular space *m* filled by the head plate *i* more or less from the middle. The head plate *i* may, as shown, extend also towards the left or in both directions, for example when employing two jacks, see Figs. 4 and 5. According to Fig. 4 the oblique longitudinal girders *a* 45 are straight throughout their entire length.

When it is a question of making the tipping frame particularly light, the middle transverse girder *h* may be omitted, as shown in Fig. 5, so 50 that an X-shaped frame is formed, in which the longitudinal girders *a* are either straight along their entire length or deflected at their ends. A spare tyre *r* is accommodated at the front between the sections *a*, *a* (Fig. 2). 55

In the form of construction shown in Fig. 5 the head-plate *i* is so long that it has two bearing points on its girder side for the engagement of one or two hydraulic jacks *f*. On each end of the frame the longitudinal girders *a* intersecting in X-shape are connected by U-section bars *k* which are welded to the longitudinal girders *a*. A correspondingly long head-plate *i* of U-shaped cross-section is placed on these transverse bars *k* and is welded thereto and also to the longitudinal girders *a*. The downwardly directed longitudinal flanges of the head-plate *i* are cut away to allow passage of the girders *a*. The two jacks *f* engage on the underside of the head-plate *i*.

The tipping frame according to the invention is light in weight, requires very little material and, owing to its oblique longitudinal girders, is particularly advantageous in that all stresses occurring during the tipping operation, irre-

spectively of whether the load slips equally or unequally, are taken up so that the tipping frame remains free from torsion. The tip bearing arms *e* need only be very short so that they cannot bend. The hydraulic jack, may engage at different points of the tipping frame to meet requirements. All these advantages cannot be attained with rectangular intersecting struts, as has already been proposed.

I claim:

An X-shaped tipping frame for the box of a wagon, comprising in combination with the rectangular tipping frame two load carrying girders intersecting in X-shape, two transverse bars under said girders, and a supporting head-plate extending under said X-shaped girders and resting on said transverse bars and destined for the engagement of hydraulic jacks.

MAX ROEDEL. 20
